PRODUCTION OF PREMIUM AVIATION FUEL
COMPONENTSSam R. Bethea, Baytown, Tex., assignor to
Standard Oil Development Company, a corpora-
tion of Delaware

Application July 13, 1945, Serial No. 604,838

5 Claims. (Cl. 260—683.6)

1

The present invention is directed to a process for producing premium aviation fuel components.

The process of the present invention may be described briefly as involving the steps of catalytically dehydrogenating a C₄ fraction containing mono-olefins in the presence of large amounts of steam to obtain a product rich in aromatics, mono-olefins and diolefins, fractionally distilling the product from the dehydrogenation step to separate a fraction including the C₆ hydrocarbons and boiling up to approximately 350° F., treating this fraction with clay to polymerize at least a major portion of the diolefin and the more reactive mono-olefins therein, separating product from the clay treating step and in distilling to separate a fraction boiling up to 350° F. and subjecting this fraction to a mild hydrogenation step to obtain a product suitable for inclusion in a premium aviation fuel.

The practice of the present invention will now be described in greater detail in conjunction with the drawing in which the sole figure is in the form of a diagrammatic flow sheet illustrating a preferred modification of the present invention.

Turning now specifically to the drawing, a C₄ fraction, for example, a C₄ fraction containing a major amount of butylenes and minor amounts of butanes, is passed through an inlet 11 and is mixed with a large amount of steam injected through inlet 12. The mixture of C₄ hydrocarbons and steam passes into catalytic dehydrogenation zone 13 where it is contacted with a catalyst under temperature and pressure conditions which cause the formation of relatively large amounts of diolefins as well as higher boiling mono-olefins and aromatics. It is preferred to maintain the catalytic dehydrogenation zone at a temperature within the range of 1050° to 1300° F. and at a pressure within the range of 1 to 2 atmospheres absolute. Under these temperature and pressure conditions the catalyst employed may be any of the known dehydrogenation catalysts, such as one consisting of 80% MgO, 14% Fe₂O₃, 3% K₂O and 3% CuO. In the catalytic dehydrogenation zone it is preferred to have superheated steam admixed with the hydrocarbons within the range of 3 to 15 volumes of superheated steam per volume of hydrocarbon and this mixture is preferably passed over the catalyst at space velocities within the range of 2 to 500 volumes of feed per volume of catalyst per hour.

Product is removed from catalytic dehydrogenation zone 13 via outlet 14 and is passed to a quenching zone 15 where the temperature of the product is reduced as rapidly as possible. In the

2

drawing, the quenching zone 15 appears as a rectangular member. In practice, it will usually be desirable to divide the quenching zone into several steps, using, for example, a water spray, an oil spray and a subsequent water spray to cool the product from the catalytic dehydrogenation zone and from each of these stages the mixture of quenching liquid and product is withdrawn and separated prior to passing the product to the subsequent stage. The quenching of the product removed from the catalytic dehydrogenation zone in itself is not considered an inventive feature in the present case and is not shown in detail in the drawing; the zone designated by numeral 15 will be understood to include as many quenching steps and separating steps as necessary in order to produce a quenched liquid product which is removed from the zone 15 through outlet 16 and passed to a distillation tower 17 provided with a heating coil 18.

In the fractional distillation tower 17, the low boiling diolefin components, such as butadiene and pentadiene, which in themselves are valuable products, are separated from the relatively less valuable higher boiling components. In the drawing, the low boiling components, which may include butadiene and pentadiene, are indicated as being withdrawn as overhead through outlet 19 while the heavier components which are indicated as being C₆ plus hydrocarbons are removed as a higher boiling fraction through outlet 20. In commercial practice it will be understood that the fractional distillation step may be conducted in a plurality of fractionating towers and a fraction containing butadiene and a fraction containing pentadiene may be separately removed from the distillation step and subjected to further treatment to concentrate the valuable butadiene and pentadiene fractions but these manipulative steps are well known to the art and are not shown in detail in the drawing.

The fraction withdrawn from the fractional distillation step 17 through outlet 20 includes the C₆ and higher boiling hydrocarbons and comprises substantial amounts of aromatic hydrocarbons as well as diolefin and mono-olefin constituents boiling in the range from about 110° to about 350° F. This fraction is treated to remove at least the major portion of the diolefins and the more reactive mono-olefins by contacting it with clay at a temperature substantially above atmospheric to polymerize the diolefin and more reactive mono-olefin constituents and the product from the clay treating step is subsequently distilled to separate it into a lower boiling con-

densate fraction and a higher boiling bottoms fraction containing the bulk of the polymer produced in the clay treating step. In the drawing, the treatment for removing the diolefin and more reactive mono-olefin is indicated by passing the C₈ and heavier hydrocarbon fraction from line 20 through furnace 21 where it is heated to a temperature substantially above atmospheric, for example, approximately 400° F., and the fraction passes from furnace 21 through line 22 to clay treating zone 23 maintained at a pressure of about 100 lbs./sq. in. Various types of clay may be employed in zone 23, such as Attapulgus clay or fuller's earth. The naphtha fraction is maintained in contact with the clay in treating zone 23 for a time interval of approximately 2 hours at a temperature of approximately 400° F. Product is removed from clay treating zone 23 through outlet 24 to a fractional distillation zone indicated as distillation tower 25 provided with a heating coil 26. In the distillation zone, the product from the clay treating zone is separated into a lower boiling fraction removed through outlet 27 and a heavier fraction containing the bulk of the polymers which are removed through outlet 28.

The fraction in line 27 is preferably obtained by operating the fractional distillation zone to produce an overhead fraction boiling up to 350° F. and this fraction, substantially free from diolefins and the more reactive mono-olefins, is subjected to a mild hydrogenation step in zone 29 to produce a product suitable for use as a premium aviation fuel base stock. It is preferred to employ a catalyst of the type of nickel sulfide-tungsten sulfide in zone 29 and to contact the vaporized naphtha with the catalyst at a temperature within the range of 400° to 600° F. The pressure within zone 29 may conveniently be within the range of 200 to 240 pounds per square inch and the volume of liquid per volume of catalyst per hour is preferably within the range of 2 to 3. On a large scale unit which allows the naphtha charge rate to be varied within the range of 8,000 to 17,000 barrels per day, the hydrogen charge rate may be within the range of 800,000 to 1,500,000 cubic feet per hour.

The product from the hydrogenation zone 29 is removed through outlet 30 and is suitable, after blending, for use as a finished premium aviation fuel. Accordingly, the product is passed to a blending step, indicated in the drawing by rectangle 31, and the finished product is withdrawn through outlet 32. It will usually be found desirable to blend the product from the mild hydrogenation step with isopentane and tetraethyl lead to obtain a finished product.

It is to be emphasized that the C₈ and heavier hydrocarbon fraction separated from the product of the dehydrogenation zone must be subjected first to a clay contacting step to polymerize the active diolefins and mono-olefins, the resulting polymer separated and the remaining material mildly hydrogenated in order to obtain a material suitable for use as a premium aviation fuel. The clay contacting step in itself will not produce a product of sufficiently high quality for use in an aviation grade fuel. If the C₈ and heavier fraction obtained from the product of the catalytic dehydrogenation zone is sent directly to a hydrogenation zone without a prior clay contacting treatment, its high gum content rapidly fouls the exposed surfaces of the equipment and soon renders the process inoperable.

The results obtained in the practice of the 75

present invention are shown in the following example:

EXAMPLE

A C₄ fraction containing approximately 80% n-butlenes, 8% isobutylene and 12% butanes was subjected to catalytic dehydrogenation at a temperature of approximately 1200° F. in the presence of a catalyst consisting of approximately 80% MgO, 14% Fe₂O₃, 3% K₂O and 3% CuO. Product from the dehydrogenation zone was quenched and fractionated and from the C₈ and heavier fraction three samples were obtained. The first of the samples was given no further treatment except blending and was subjected to inspections, the results of which are set out in column 1 of the following table. The second sample was subjected to a clay treatment step and the conditions of the treatment and characteristics of the product resulting from the treatment are set out in column 2 of the table below. The third sample was subjected to a clay treatment under the same conditions as the sample of column 2 and from the product of the clay treatment was separated a distillate fraction boiling within the range of C₈ to 350° F.; this latter fraction was hydrogenated at a temperature of 450° F., a pressure in the range of 160 to 170 lbs./sq. in., and the feed rate of the hydrogen and naphtha adjusted to a mole ratio of 4.25:1 in the presence of a nickel sulfide-tungsten sulfide catalyst with the ratio of naphtha feed (liquid volumes) per catalyst volume equal to .83:1. The product from the mild hydrogenation step was then subjected to the same inspections as the fractions listed in columns 1 and 2, and the results were entered in column 3.

Table

	None	Clay Treated	Clay Treated and Hydrogenated
<i>Treatment Given to Bottoms</i>			
45 Clay Treater Employed		(¹)	(¹)

¹ Fixed bed.

It will be seen that the product obtained when dehydrogenating a C₄ fraction in the presence of steam and catalyst was given a clay treatment with a subsequent hydrogenation treatment resulted in a material which when blended with isopentane and tetraethyl lead had an aviation octane number of slightly above 95.

While I have given a specific example illustrating the practice of the present invention and have given preferred operating conditions, it will be understood that these conditions are not intended to be limitations but are given solely for

the purpose of illustrating the practice of the invention.

Having fully described and illustrated the present invention, what I desire to claim as new and useful and secure by Letters Patent is:

1. A method for producing premium aviation fuel components including the steps of catalytically dehydrogenating a C₄ fraction including a major amount of normal mono-olefin to produce a product including substantial amounts of mono-olefin, diolefin and hydrocarbons boiling above 110° F. distilling the resultant product to separate a fraction boiling in the range of 110° to 350° F., contacting said fraction with clay at a temperature of approximately 400° F. to polymerize at least a major portion of the diolefin therein, removing product from said clay treating step, distilling to separate a fraction boiling up to 350° F. and mildly hydrogenating it to obtain a fraction suitable for inclusion in a premium aviation fuel.

2. A method in accordance with claim 1 in which the mild hydrogenation step is conducted at a temperature within the range of 400° to 600° F. in the presence of a nickel sulfide-tungsten sulfide catalyst.

3. A process for producing premium aviation fuel components including the steps of passing a vaporized C₄ fraction including normal mono-olefin into a dehydrogenation zone where it is brought into contact with a dehydrogenating catalyst in the presence of steam to form substantial amounts of diolefin, mono-olefin and hydrocarbons boiling above 110° F. therein, removing product from said dehydrogenation zone, 30 fractionally distilling said product to separate a

fraction boiling in the range of approximately 110° to 350° F., and contacting said fraction with clay at a temperature of approximately 400° F. for no less than approximately two hours to cause substantially complete polymerization of the diolefin present therein, removing product from said clay contacting zone and fractionally distilling to separate the fraction boiling up to 350° F. and catalytically hydrogenating said fraction under mild conditions to produce a product suitable for inclusion in a premium aviation fuel.

10 4. A method in accordance with claim 3 in which said mild hydrogenation step is conducted at a temperature within the range of 400° to 600° F. and in the presence of a nickel sulfide-tungsten sulfide catalyst.

15 5. A process in accordance with claim 3 in which the dehydrogenation zone is maintained at a temperature within the range of 1050° to 1300° F. and in which the hydrogenation zone is maintained at a temperature within the range of 400° to 600° F. and in which nickel sulfide-tungsten sulfide is employed as the hydrogenation catalyst.
